UNITED STATES PATENT OFFICE.

SIMON L. MCCOLLOCH, OF WHEELING, WEST VIRGINIA.

GATE.

SPECIFICATION forming part of Letters Patent No. 641,464, dated January 16, 1900.

Application filed December 20, 1898. Serial No. 699,797. (No model.)

To all whom it may concern:

Be it known that I, SIMON L. MCCOLLOCH, a citizen of the United States, residing at Wheeling, in the county of Ohio and State of West Virginia, have invented or discovered a new and useful Improvement in Gates, of which the following is a full, clear, and exact description, reference being had to the accompanying drawings, forming part of this specification, in which—

Figure 1 is a plan view of my improved gate and its operating mechanism, the gate being shown as closed across the roadway. Fig. 2 is a similar view showing the gate open. Fig. 3 is an elevation of Fig. 2. Fig. 4 is a plan view of the operating cables and sheaves, illustrating an arrangement whereby the levers operate in a direction toward the gate. Fig. 5 is a perspective detail view of a portion of the gate, showing the latch in engagement as operated to unlatch by upward movement of the outer end of the locking-bar and in the position of the gate when closed across the roadway. Fig. 6 is a similar view from the opposite side of the gate, the gate being retained in its open position, as in Fig. 2, and the locking-bar in engagement as operated to unlatch by downward movement of the outer end of the locking-bar. Fig. 7 is a view similar to Fig. 3 looking in the direction of the arrow *a* of Fig. 1. Fig. 8 is a perspective detail view illustrating the operative mechanism by which the locking-bar is raised and lowered and the gate swung on its hinges. Fig. 8^a is a detail view illustrating a modified construction of the end of the latch-operating lever. Fig. 9 is a detail view, in front elevation, of the operating-lever and its connections. Fig. 10 is a perspective view of the same parts shown in a reversed position. Fig. 11 is a detail plan view of the adjustable hinge-strap for the lower hinge. Fig. 12 is a detail view illustrating a modified form of lever. Fig. 13 is a diagrammatic detail view in plan, illustrating the relative positions of the upper and lower hinge-hooks.

My invention relates to automatically-operated gates, and has for its object the construction of a gate that may be opened and closed by the occupant of a vehicle without alighting on the ground, and retained in position until closed.

Referring to the drawings, 2 is the post upon which the gate 3 is hung by upper and lower hinges 4 and 5. The upper hinge is formed, preferably, of a bracket 6, secured to the gate and pivotally mounted on a hinge-hook projecting outwardly from the post 2. The lower hinge is similar in construction and likewise projects outwardly from the post, but somewhat beyond the upper hinge. Both hinge-hooks are attached to that side of the hinge-post toward which the gate opens, and the lower hook is set nearer to the front of the post and slightly farther out from its face than the upper one, thus occupying a position vertically beyond the upper hook intermediate between the right-angled positions of the gate when opened or closed. By this means the gate will swing by gravity toward one side or other after passing such intermediate position. The strap 7 of the lower hinge is adjustably secured on the under side of the gate-frame by bolts passing through slots 8, thereby permitting the strap to be set in or out to provide for subsequent adjustment of the gate after setting in case of sagging or warping of the frame.

It will be seen that I employ a post 9, located across the roadway, and another post 10 at right angles to such post, against which posts the gate is swung in either the closed or open position and secured by latches, as shall be hereinafter more fully described.

Upon the post 9 is a rigid latch 11, preferably slotted for adjustment on the retaining-bolts and provided with an upper retaining-shoulder 11', adapted to engage the end of a locking-bar 12, pivoted at 13 in the frame of the gate, the locking-bar in such case operating to unlatch by upward movement. Upon the other post 10 is a pivoted latch 14, mounted in a keeper 15, permitting upward movement to engage the bar when the gate is swung around to the open position, the keeper preventing dropping of the latch, and the locking-bar 12 in this position operates to unlatch by downward movement. It will be readily understood that these latches may be reversed, if desired, the locking-bar in such case operating in a reverse manner to that described, such change simply involving a reverse action of the operating mechanism hereinafter described.

Motion is imparted to the locking-bar by means of a bell-crank lever 16, pivotally mounted at 17 in a bracket 18, secured to the upper frame of the gate, the projecting lower arm 19 of the lever being connected to bar 12 by intervening connecting-link 20.

A dog or movable attachment 21 is pivoted at 22 to the bracket 18, and its free end 23 engages the upper end of arm 24 of the lever 10 and acts to throw such arm outwardly and arm 16 downwardly by forward movement of the dog, the end 24 of the lever having a limited movement in a recess in the bracket. Lugs 25 on the bracket serve as limiting-stops 15 for the dog in either position of use, as illustrated in Figs. 8 and 10, and when the dog is withdrawn the upper end of the lever will be thrown against it, and the lower arm 16 will be raised by retractile action of a spring 20 26, secured to such lower arm and to the bracket, by which the inner end of the locking-bar 12 is raised and the outer end lowered to release it from the latch immediately before closing the gate. In the closed position 25 of the gate the outer end of the locking-bar is first raised from engagement with the latch 11 by downward movement of the inner end of the bar previous to opening the gate, such downward movement being imparted through 30 the downward action of the lever and link 20, operated by pressure of the dog 21 at the commencement of the operation of opening the gate. Movement is imparted to the dog through a pitman connection 27, attached to 35 a crank-arm 28, mounted on a grooved wheel 29, which has a partial rotatory movement, and which in its action around the central bolt 30, secured to post 2, upon which the wheel 29 is mounted, will swing the gate on its hinges to 40 either of the positions illustrated—i. e., open or closed.

Located along the side of the roadway, preferably in line with the post 2 or in other position, as desired, are the posts 31 32, to 45 which are secured brackets 33, upon which are pivotally mounted the operating grooved wheels 34 35, each wheel being provided with an operating-arm 36 or 36', projecting outwardly toward the middle of the roadway, so 50 as to be within easy reach of the occupant of a vehicle. It will be noticed that these arms project forwardly away from the direction of an approaching vehicle, in which case the occupant would operate the wheel by drawing 55 back on the arm, although, as illustrated in Fig. 4, they may be located normally in the reverse position, thus permitting the forward movement of the vehicle to be utilized in turning the wheels. These operating-wheels 34 35 60 are connected with the wheel 29 by cables 37 38, one of such cables being crossed in order to transmit rotatory motion to wheel 29, always in the same direction by corresponding outward movement of arms 36 36' or inward 65 movement of such arms when arranged as in Fig. 4.

Referring to the principal figures of the

drawings, movement of the wheel 29 when the gate is closed will first act through pitman 27 to throw the dog 21 against the upper end of 70 arm 24, throwing the arm 16 and link 20 downwardly and raising the outer end of bar 12 from engagement with latch 11, releasing the gate, which will then swing around under continued pressure of pitman 27 and dog 21, 75 bearing against the lever and bracket until it is opened. Upon striking against the post 10 the outer end of bar 12, still in a raised position, will ride under pivoted latch 14 and be engaged thereby, thus securing the gate in an 80 open position, when the pivotal end of the crank-arm 28 will have swung around into position (shown in Fig. 2) slightly past the center line of the crank and pitman, thus further locking the parts in position in the manner of a toggle-joint. In this position the lever 28 abuts against any suitable stop, as an extension 39 of post 2, where it will be held until operated in the reverse position. It will be seen that the other operating-lever 36' 90 will have been thrown into the position shown in Fig. 2 by tension of the cable 38, in which position it will be within easy reach to operate to close the gate after the vehicle has passed through. In such position movement 95 of the wheel 35 in the direction of the arrow will act through cable 36 to reverse the movement of wheel 29, throwing crank-arm outwardly, withdrawing pitman 27, releasing the pressure of the dog, and permitting spring 26 100 to raise the inner end of bar 12, throwing the outer end down and releasing it from engagement with the latch. Continued movement of the wheels and crank-arm 28 will swing the gate around until it is closed, when it will 105 ride over the latch 11, thus completing the operation.

It will be understood that the pitman 27 might, if desired, be connected directly to the upper end of arm 24 of the lever; but I prefer the construction shown, for the reason that it permits independent action of the locking-bar by simply raising it by hand, as in the ordinary manner. However, if it is desired to make such a connection the end of the lever 115 may be vertically slotted, as shown in Fig. 8^a, thus permitting such independent upward movement of the bar, while not interfering with the already-described operation through the operating-wheels. The pressure by contact through the dog is also preferable to a direct connection, for the reason that there is freer action and less tendency to bind, owing to the varying angle existing between the pitman and the general direction of movement 125 of the arm 24 of the lever. Also, it will be understood that the lever 16 may be made with a downward extension 19', as shown in Fig. 12, having a connection with a sliding locking-bar 12', adapted to engage suitable 130 recesses or hasps secured to the posts 9 and 10.

It will be understood that when the wheels 34 35 and levers 36 36' are arranged as shown in Fig. 4 the action of the cables will be re-

versed, in which case the shorter cable is made straight and the longer one crossed, and the location of the actuating-wheels, their direction of movement, and the relative arrangement of the posts may be changed by the skilled mechanic to suit varying conditions of use and as circumstances require.

The operation of the gate being in one direction, it is obvious that one of the operating-wheels may be placed nearer to the gate than the other, as the vehicle may be made to approach nearer on that side than on the side toward which the gate swings by such distance as is required for clearance.

15 The advantages of my invention will be appreciated by those skilled in the art, and it will be found to be applicable to a wide variety of conditions of use with equal advantage—as, for instance, on grades, curved 20 roads, &c.

An especial advantage in the use of the grooved sheave-wheels lies in the fact that the cables, by reason of always leading off from or onto their peripheries, always exert 25 the greatest possible leverage on such wheels.

Changes and variations may be made in the design, proportions, or general arrangement without departing from my invention, since I do not desire to be limited to the exact construction shown in the drawings, but to include all such changes as within the scope of the invention as embodied in the following 30 claims.

Having described my invention, what I 35 claim is—

1. A swinging gate provided with a pivotally-mounted latching-bar, a lever mounted on the gate connected to and adapted to actuate the latching-bar, an actuating crank-arm mounted independent of the gate, a connecting-pitman attached to the crank-arm and to a movable attachment on the gate adapted 40 to operate said lever by bearing against one side thereof, and means for operating the 45 crank-arm.

2. A swinging gate provided with a pivotally-mounted latching-bar, a lever mounted on the gate connected to and adapted to actuate the latching-bar, an actuating crank-arm mounted independent of the gate, a connecting-pitman attached to the crank-arm and to a movable attachment on the gate adapted 50 to operate said lever by bearing against one side thereof, and to transmit swinging movement to the gate.

3. A swinging gate provided with a pivotally-mounted latching-bar, a lever mounted on the gate connected to and adapted to actuate the latching-bar, an actuating crank-arm mounted independent of the gate, a connecting-pitman attached to the crank-arm and to a movable attachment on the gate adapted 60 to operate said lever by bearing against one side thereof, a hand-lever, and operating mechanism connected with the actuating crank-arm and with the hand-lever.

4. A swinging gate provided with a pivot-

ally-mounted latching-bar, a lever mounted on the gate connected to and adapted to actuate the latching-bar, an actuating crank-arm mounted independent of the gate, a connecting-pitman attached to the crank-arm and to a movable attachment on the gate adapted 70 to operate said lever by bearing against one side thereof, an operating-wheel 75 secured to the actuating crank-arm, an actuating-wheel mounted independent of the operating-wheel and provided with a hand-lever, and a power-transmitting connection between the actuating-wheel and the operating-wheel.

5. A swinging gate provided with a pivotally-mounted latching-bar, a lever mounted on the gate connected to and adapted to actuate the latching-bar, an actuating crank-arm mounted independent of the gate, a connecting-pitman attached to the crank-arm and to a movable attachment on the gate adapted 80 to operate said lever by bearing against one side thereof, an operating-wheel 85 secured to the actuating crank-arm, and oppositely-disposed actuating-wheels mounted independent of the operating-wheel and provided with hand-levers, and power-transmitting connections between such actuating-wheels and the operating-wheel.

6. A swinging gate provided with a pivotally-mounted latching-bar, a lever mounted on the gate connected to and adapted to actuate the latching-bar, an actuating crank-arm mounted independent of the gate, a connecting-pitman attached to the crank-arm and to a movable attachment on the gate adapted 90 to operate said lever by bearing against one side thereof, an operating-wheel 95 secured to the actuating crank-arm, and oppositely-disposed actuating-wheels mounted independent of the operating-wheel and provided with hand-levers, and connected with the operating-wheel by intervening cables.

7. A swinging gate mounted on a post provided with an abutment, mechanism for latching the gate, a wheel pivotally mounted on the post, a crank-arm secured to the wheel and adapted to bear against the abutment, 105 an actuating-wheel provided with a hand-lever and cables connecting such wheel with the wheel carrying the crank-arm, and a connecting-pitman attached to the arm and to the mechanism for latching the gate and 110 adapted to coöperate with the crank-arm to bind the parts in position.

8. Means for swinging and locking a gate consisting of a crank-arm mounted on the gate-post, a pitman connected to the crank-arm and to a movable attachment on the gate, and an abutment against which the crank-arm is adapted to bear and by which its motion is arrested.

9. Means for swinging and locking a gate 125 consisting of a crank-arm mounted on the gate-post, a pitman connected to the crank-arm and to a movable attachment on the gate whereby movement of the crank-arm will im-

part swinging motion to the gate, the crank-arm and pitman assuming a position in alignment with each other at the limit of motion of the gate, and an abutment against which the crank-arm is adapted to bear upon a slight further additional movement of the crank-arm and by which its further movement is arrested beyond the alining position of the crank-arm and pitman, so as to lock the parts in position.

10. In mechanism for unlatching and swinging a gate: a lever mounted on the gate connected to and adapted to actuate a latching-bar and adapted to transmit swinging movement to the gate, an actuating-dog, a pitman connected with the dog, and an operating-crank connected with the pitman, substantially as set forth.

11. In mechanism for unlatching and swinging a gate, a bracket mounted on the gate, a lever connected to a latching-bar and having a limited movement in the bracket, a pivoted dog mounted on the bracket adapted to engage the lever, a connecting-pitman attached to the dog, and an operating-crank connected with the pitman, substantially as set forth.

12. In mechanism for unlatching and swinging a gate; a bracket mounted on the gate, a lever mounted on the bracket connected with a locking-bar and having a limited movement in the bracket, a retracting-spring attached to the lever, a shifting-dog adapted to engage the lever and an operating-crank mounted independent of the gate and connected by a pitman, with the shifting-dog, substantially as set forth.

13. In mechanism for unlocking and swinging a gate: a bracket mounted on the gate, a lever mounted on the bracket connected with a locking-bar and having a limited movement in the bracket, a shifting-dog mounted on the bracket adapted to engage the lever, limiting-stops for the dog, a retracting-spring attached to the lever, a connecting-pitman attached to the shifting-dog, and an operating crank-arm mounted on a sheave-wheel and attached to the connecting-pitman with means for imparting partial rotatory movement to the sheave-wheel, substantially as set forth.

14. In mechanism for unlocking and swinging a gate: a bracket mounted on the gate, a lever mounted on the bracket connected with

a locking-bar and having a limited movement in the bracket, a shifting-dog mounted on the bracket adapted to engage the lever, limiting-stops for the dog, a retracting-spring attached to the lever, a connecting-pitman attached to the shifting-dog, and an operating crank-arm mounted on a sheave-wheel and attached to the connecting-pitman and sheave-wheels provided with crank-handles and connected with such crank-operating sheave-wheel by intervening operating-cables, substantially as set forth.

15. In mechanism for unlocking and swinging a gate: a bracket mounted on the gate, a lever mounted on the bracket connected with the locking-bar and having a limited movement in the bracket, a shifting-dog mounted on the bracket adapted to engage the lever, limiting-stops for the dog, a retracting-spring attached to the lever, a connecting-pitman attached to the shifting-dog, and an operating crank-arm mounted on a sheave-wheel and attached to the connecting-pitman with means for imparting a partial rotatory movement to the sheave-wheel and crank-arm and means for limiting the movement of the crank-arm, substantially as set forth.

16. In a fence, the combination of a supporting-post, a gate hinged thereon provided with a pivotally-mounted latching-bar, posts for limiting the swinging movement of the gate at open and closed positions respectively provided with latches adapted to engage the latching-bar, a lever mounted on the gate and connected with the latching-bar, a movable attachment mounted on the gate and adapted to engage the lever, a pitman connected therewith and with a crank-arm, a sheave-wheel secured to the crank-arm and pivotally mounted on the gate-post, operating sheave-wheels located on opposite sides of the gate-post provided with handles and connecting-cables or the like adapted to transmit motion from the operating sheave-wheels to the crank-arm sheave-wheel.

In testimony whereof I have hereunto set my hand.

SIMON L. McCOLLOCH.
